UNITED STATES PATENT OFFICE

2,481,822

OVERHEAD TRACK SWITCH OPERATING LEVER

John A. Carlsen, Winona, Minn.

Application July 19, 1946, Serial No. 684,912

7 Claims. (Cl. 74—469)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to a hand-operated lever device for switches on overhead tracks. It is particularly designed to operate on overhead tracks for travelers employed to suspend and convey meat food products and the like.

The object of my invention is to provide a switch-operating means which operates easily and quickly from any height with a short upward or downward stroke of a control rod, can be attached directly to standard switches, can be lengthened or widened in any direction to assure clearance of the control rod from the material suspended from the track, and which is certain in operation.

I attain these objects by the device illustrated in the accompanying drawing, in which

Figure 1 is a view of the switch-operating means in open switch position.

Figure 2 is a view of the device in closed switch position.

The switch may be of any conventional design. That shown in the drawings comprises a straight track section 1 and a curved section 2 for controlling a diverging route. The curved section 2 is attached to plate 3 which is pivoted at 4. The straight section 1 pivots on bracket 5. Upon closing the switch, that is, upon moving the straight section downwardly to the left in Figure 1, projecting cam 6 attached thereto is introduced into aperture 7 in the plate 3. The surface of the cam bears against an edge of the aperture, causing the curved section to rotate about its pivot. To raise the straight section the arm 8 is rotated downwardly. Toward the end of its downward movement the arm engages the edge of the plate 3 and pushes it back into the position shown in Figure 1, locking it in that position. The arm 8 may be integral with a switch element as shown in the drawing, or it may be removably attached thereto. Rigidly attached to arm 8 is a curved bar 9, carrying a bolt stud 10, which stud may also serve to attach the bar to the arm 8. The means for raising and lowering the arm and bar comprise a lever 11 pivoted at 12 on fixed rod 13, which rod is bent for convenience in operation, a second lever 14 to operate the first lever, pivoted at 15 on the same fixed rod, and a control rod 16 to push or pull the second lever. Lever 11 is bifurcated at the left end to provide a finger 17 which

2

engages and holds the stud 10 in the position shown in Figure 2. The upper part 18 of the bifurcated end carries a swivel eye 19 rotatably mounted thereupon. Upon movement of the left part of lever 11 downwardly the swivel eye slides downwardly upon curved bar 9, forcing it downward.

The operation is as follows:

Figure 1 shows the curved track section 2 in place and the straight track section 1 raised. Upon pushing the control rod 16 upwardly lever 14 bears downwardly against the right arm of lever 11, through a stationary eye thereon. The left part of lever 11 is thereby raised, causing the swivel eye 19 to slide to the left and upwardly upon the curved bar. During this upward motion the finger 17 engages the stud 10 to assure complete closing of the switch, in the position shown in Figure 2.

Figure 2 shows the straight track section 1 lowered into place. To raise this section and rotate the curved section into place, the control rod is pulled down. The parts may be so proportioned that a travel of 4 inches will suffice to open or close the switch. Upon pulling the control rod, the left part of lever 11 is moved down, pushing the stud 10, the arm 8, and curved bar 9 downward. Upon further movement of the lever the curved edge of part 18 of the lever slides downward and to the right, eventually disengaging with the stud. At this point, the swivel eye 19, which rotates on a bolt in the end of lever 11, slides downwardly and backwardly on the curved bar 9, forcing the latter downward to complete the raising of the straight track section to the position shown in Figure 1.

Having thus described my invention, I claim:

1. An overhead track switch operating apparatus for moving a track section into and away from track connecting position, comprising a pivotally mounted arm, operably connected to the track section to move it as aforesaid; a bar rigidly attached to said arm at an angle thereto at a point removed from the pivot of the latter, said bar having a concave surface directed toward the upper surface of the arm, and a convex surface opposite the concave surface; a lever mounted upon a fixed pivot and operably connected to rotate said arm and bar about the pivot of the arm; means for moving the said lever about its pivot, said lever having a bifurcated end providing a lower finger and an upper portion having an outwardly convex end surface; a member mounted on said upper portion, said member having means that bears upwardly against and slides along the

convex surface of the arm during upward movement of the bifurcated end and which bears downwardly against and slides along the concave surface of the arm during downward movement of the bifurcated end; a stud attached to the bar and arm unit at or adjacent to the juncture of the bar and arm, said lever, arm, and bar being so positioned that the lower finger bears upwardly against the stud when the bifurcated lever end is moved upwardly, and being so positioned that, upon downward movement of the said bifurcated lever end, the convex end surface thereof rides on the stud pushing it downwardly until a point is reached at which the stud and bifurcated end are no longer in contact, whereupon the said means bears upon and slides upon the concave surface of the bar, forcing the latter downwardly to complete the movement of the arm, said means bearing upwardly against the convex surface of the bar in the initial part of the upward movement of said bifurcated end.

2. The apparatus defined in claim 1, in which the means for moving said lever comprises a second pivotally mounted lever, a rod for pulling an end of the second lever down and for pushing it up, the second lever being operably connected to move the first lever.

3. The apparatus defined in claim 1, in which the member rotatably mounted on the upper portion of the bifurcated end is a swiveled-apertured member mounted at the side of said upper portion in position to permit the bar to slide therewithin.

4. A track switch operating apparatus for moving a track section into and away from track connecting position, comprising a pivoted arm, operably connected to move the track section as aforesaid; a bar rigidly attached to said arm at a point removed from the pivot of the latter and forming an angle less than 180° with the upper surface of the arm; a stud fixedly attached at or adjacent to the juncture of said arm and bar; a lever operably connected to rotate said arm and bar about the pivot of the arm, said lever having adjacent one end a lower finger which engages the stud and thereby supports the pivoted arm upon upward movement of the lever and an upper portion carrying means slidably engaging the bar to move it downwardly upon downward movement of the said lever end and to move it upwardly upon upward movement of said lever end.

5. An overhead track switch operating apparatus for pivoting a track section downwardly and upwardly toward and away from track connecting position, comprising a pivoted arm movable upwardly and downwardly and operably connected to raise and lower the track section as

aforesaid; a bar rigidly connected to said arm at an angle thereto and at a point removed from the pivot of the arm; said bar being provided with upper and lower cam surfaces one of which is a concave surface facing toward the pivot of the arm; a lever operably connected to turn said arm and bar about the pivot of the arm; said lever having adjacent one end means which slidably engages the said concave surface to move the bar downwardly upon downward movement of said lever end; and to slidably engage the second of said cam surfaces to move the bar upwardly upon upward movement of said lever end.

6. The apparatus of claim 5, and a fixed bracket extending laterally away from the track section; the said lever being pivoted upon said bracket; and a manually operable second lever pivoted upon said bracket at a point farther removed from said track section than the pivot of the first lever; the second lever being operably connected to turn the first lever.

7. An overhead track switch operating apparatus for pivoting a track section downwardly into track connecting position and upwardly away from track connecting position, comprising a pivoted arm movable upwardly and downwardly, and operably connected to raise the track section upon movement downwardly and to lower the track section upon movement upwardly, a bar rigidly connected to said arm at an angle thereto and at a point removed from the pivot of the arm; said bar being provided with upper and lower cam surfaces one of which is a concave surface facing toward the pivot of the arm; a lever operably connected to turn said arm and bar about the pivot of the arm; said lever having toward one end means which slidably engages the said concave surface to move the bar downwardly upon downward movement of said lever end, and to slidably engage the second of said cam surfaces to move the bar upwardly upon upward movement of said lever end; and means mounted adjacent the junction of the arm and bar which interlocks with said lever end upon upward movement of the lever end.
